THOMAS M. RIGGLE, OF OAKLAND, CALIFORNIA, ASSIGNOR OF ONE-EIGHTH TO
LIDA E. RIGGLE, OF OAKLAND, CALIFORNIA.

AUTOMATIC TRAIN STOP.

1,426,321.

Specification of Letters Patent. Patented Aug. 15, 1922.

Application filed September 4, 1920. Serial No. 408,365.

To all whom it may concern:

Be it known that I, THOMAS M. RIGGLE, a citizen of the United States, residing at Oakland, in the county of Alameda and State 5 of California, have invented a new and useful Improvement in an Automatic Train Stop, of which the following is a specification.

My invention relates to improvements in 10 automatic train stops wherein a brake valve actuating mechanism, adapted to set the air brakes on a train or the like, is arranged to be operated at regular intervals of distances traversed by said train over a track comprising 15 insulated sections of various lengths, and operates in conjunction with mechanism, or any standard block signalling system, to reset a retarding mechanism at a predetermined distance in advance of the farther end 20 of an approaching insulated section provided said section is "clear" and to prevent such resetting if for any reason said section is not clear, or the standard block signaling system of said section is not in proper working 25 order.

The primary object of the present invention is to provide a new and improved automatic train stop adapted to automatically stop a train or the like before entering a 30 "closed" or "blocked" track section.

A further object is to provide a device of the character described wherein the train stop will be actuated should any portion thereof become broken or out of order, due 35 to such defects as air leaks or broken electric circuits in the various connections.

A still further object of the invention is to provide improved means for actuating the standard brake valve now used on trains 40 without interfering with the proper manipulation of said valve by the engineer or motorman, under normal conditions.

A further object of the invention is to provide simple and improved means for resetting a retarding mechanism just previously to the entrance of a train into an insulated track section provided said section is "clear" and to prevent resetting of said retarding mechanism if said section is not clear. 45

A still further object of the invention is to provide an improved device of the character described wherein improved means are provided to reset a retarding mechanism at

a predetermined distance in advance of the farther end of an insulated section, where- 55 by said retarding mechanism may be operated to release the brake valve actuating mechanism just previously to the entrance of a train into the next adjacent section.

I accomplish these and other objects by 60 means of the improved device disclosed in the drawings forming a part of the present specification wherein like characters of reference are used to designate similar parts throughout the said specification and drawings, and in which:

Fig. 1 is a broken elevation of a portion of a locomotive tender and one of the trucks thereof resting upon a section of track and adjacent to a resetting jumper, or operating 70 contact, disclosing my improved device attached thereto;

Fig. 2 is an enlarged broken elevation of the device removed from the truck;

Fig. 3 is a broken plan view of Fig. 2; 75

Fig. 4 is an enlarged broken detail view of the automatic reversing mechanism whereby the retarding mechanism is moved forward when the direction of movement of the train is reversed;

Fig. 5 is an enlarged transverse sectional view of a section of track disclosing the resetting contacts or jumpers, including a diagrammatic view of the engine circuit of the resetting mechanism;

Fig. 6 is a diagrammatic view of several adjoining insulated track sections disclosing the operation of the invention;

Fig. 7 is a broken plan view of a standard brake valve disclosing the brake valve 90 actuating mechanism applied thereto;

Fig. 8 is a broken detailed view of a portion of the brake valve disclosing the manner in which the same is engaged and disengaged by the actuating mechanism therefor;

Fig. 9 is an end elevation of a portion of Fig. 8; and

Fig. 10 is a broken detailed view of the resetting valve and contacts. 100

Referring to the drawings the numeral 1 is used to designate a portion of a locomotive tender provided with the usual truck 2 having wheels 3 mounted upon standard axles 4. Upon one end of one of the axles 4 I have 105 mounted an extension 6 provided with a pin-

ion 8 which drives a gear 9 having a pinion 11 meshing with the gear 12 which in turn rotates a shaft 14 upon which is slidably mounted or feathered a double ended clutch member 16 arranged to engage either one of a pair of clutch members 17 and 18 connected to oppositely faced or positioned bevel gears 19 and 20, respectively, loosely mounted upon the shaft 14. The bevel gears 19 and 20 are constantly in mesh with a third bevel gear 22 rotatably mounted within a suitable bearing 23 and connected to a bevelled pinion 24 which in turn meshes with and rotates a beveled gear 26 having a knurled edge, the purpose of which will hereinafter be more fully described.

Rotation of the axle 4 in a clockwise direction, assuming that the train is moving forward and toward the right, will, through 20 the train of gears above described, rotate the beveled gear 26 clockwise as indicated by the curved arrows in Fig. 1 of the drawings.

Also connected to and rotating with the axle 4 is a bevel pinion 28 meshing with and 25 rotating a bevel gear 29 connected to a disc 31 provided with a plurality of flat convexed pins 32 arranged at regular intervals annularly on one face of said disc 31 and adjacent the periphery thereof, said pins 32 engaging the flexible end 33 of a lever 34 operatively connected to the double ended clutch member 16 on the shaft 14. Rotation of the disc 31 will cause the pins 32 thereon to engage said flexible end 33 and therefore 35 by retain the double ended clutch member 16 in engaging relation with either one of the clutch members 17 and 18 of the bevel gears 19 and 20, respectively, as disclosed in Fig. 4 of the drawings, the purpose of 40 which novel arrangement will hereinafter be more fully set forth.

Pivottally mounted upon the shaft 36 of the bevel gear 26 is an arm 37 extending slightly beyond the periphery of said gear 45 26 and having pivotally mounted thereon an eccentric cam 38 arranged to engage the knurled periphery of said gear 26 when said cam 38 is moved in one direction, and to release said periphery when moved in the opposite direction.

A link 39 pivotally connects an extension 41 of the cam 38 to a piston stem 42 having large and small pistons 43 and 44 mounted upon opposite ends thereof and slidably 55 mounted within large and small cylinders 46 and 47 respectively, the said cylinder 47 having a V-shaped slot cut in the open end thereof, the purpose of which will hereinafter be more fully described.

60 The hereinbefore mechanism may be set within a suitable housing or box 49 for protective purposes.

A pipe connection 51 connects the cylinder 46, which for purposes of illustration shall 65 hereinafter be termed a resetting cylinder,

with the main reservoir, not shown, of any standard air brake system.

The pipe 51 is provided with a valve 52 which is normally held closed by a spring 53 attached to an arm 54 of the valve 52, said arm 54 being pivotally connected to and operated by a solenoid 56.

The cylinder 47, which shall hereafter be termed a releasing cylinder, is connected by means of a pipe 58 to a brake valve actuating cylinder 59 which in turn is connected to the application pipe 61 of the air brake system hereinbefore referred to.

Slidably mounted within the actuating cylinder 59 is a piston 62 the stem 63 of which has its outer end slidably mounted upon a standard brake valve indicated in general by the numeral 64, as disclosed in Fig. 7 of the drawings. The stem 63 is provided with a pivotally mounted and spring 85 controlled pawl 66 having a depending arcuate flange 67 thereon to engage a lug 68 on an extension 69 of the brake valve control lever 71. The flange 67 of the pawl 66 when moved toward the left is arranged to engage the lug 68 of the lever 71, when in running position, and move the same to service position when the piston 62 is actuated, and to release said lug 68 when said pawl is moved toward the right. In other 95 words, the operating lever 71 of the brake valve 64 is free to be moved to any position at all times, and is only engaged by the pawl 68 and moved from running to service position when the automatic train stop is operated.

A pipe connection 73 leads from the main brake pipe, not shown, of the standard air brake system to the actuating cylinder 59 and on the opposite side of the piston 62 105 therein from the application pipe 61. The pipe connection 73 is provided with a three way cock 74 arranged to normally permit the passage of air under pressure to the actuating cylinder 59, when in one position 110 and to prevent the passage of air to said cylinder and open the same to the atmosphere when in the opposite position.

The valve 74 is normally held in the first mentioned position by means of a suitable 115 spring 75 connected to the operating lever 76 of said valve 74, and said lever 76 carries an arm 77 adapted to close an electric switch 78 when moved to open the actuating cylinder 59 to the atmosphere, the purpose 120 of which will hereinafter be more fully set forth.

A contact shoe 81 is mounted upon a bar 82 of any suitable insulating material on each side of the train, which bar has its ends 125 slidably mounted within slotted cylinders 83 depending from the truss rods or struts of the truck 2 and suitable springs 84 are interposed between the said ends and the upper ends of said cylinders 83 whereby 130

said shoe 81 may be normally depressed to contact with track trips 86, arranged on each side of the rails 87. The lower edges of the contact shoes 81 are preferably beveled 5 as disclosed in Fig. 5 of the drawings.

Referring to Fig. 5 of the drawings, a suitable cable 88 leads from one contact shoe 81 to a source of electrical energy, such as a battery 89 or the like, while a second 10 cable 91 leads from the other side of said battery 89 to the solenoid 56 hereinbefore described and from thence a cable 92 leads to the other contact shoe 81 on the opposite side of the train.

15 The switch 78 hereinbefore described and disclosed in Figs. 7 and 10 of the drawings is connected in series with the battery 89 and solenoid 56 by means of suitable wires or connections 93 whereby the solenoid 56 may 20 be operated independently of the automatic train stop if required.

The track, comprising the two parallel rails 87, is divided into insulated sections as at present in common use with standard 25 block signalling systems, and the present invention may be used in conjunction with said standard systems all of which are substantially the same in this respect, viz; a battery 94 has the opposite sides thereof connected to opposite rails 87 of each section, while at another portion of said section an electro-magnet 96 or what is commonly known as a track relay, is connected in series 30 with the rails 87 and battery 94. The track 35 relay being energized, when that track section is "clear," an armature 97 is attracted to close contact, by means of a member 98, between a pair of terminals 99 of wires 100 connected to the track contacts 86. The 40 track sections and electrical connections pertaining to each track section will hereinafter be designated as blocks to differentiate the same from said track sections.

For purposes of illustration the wires 100, 45 contacts 99, member 98 and track shoes 86 will herein be termed a jumper as it serves to carry or jump current from one contact trip 81 to the other.

If any of the wires or connections in the 50 circuit of any block should become disconnected, broken or otherwise inoperative, or if the block circuit through the rails 87 of any section become shorted by the presence of a train or other pair of wheels in that 55 section, the current from the track battery 94 will be shorted and the track relay 96 will be de-energized and the member 98 will drop, being actuated by gravity, to break the connection between the contacts 99 and 60 therefore no current can pass from the battery 89 in the train to energize the solenoid 56.

The operation of the automatic train stop is as follows:

65 While the train is in motion the operating

lever 71 of the brake valve 64 will be positioned in the running position and the pawl 66 on the stem 63 will lie slightly beyond the lug 68 of the extension 69 of the said operating lever 71, as disclosed in Fig. 7 of 70 the drawings.

The pawl 66 is held in this position by the pressure of air in the application pipe 58 or 61 side of the piston 62 in the actuating cylinder 59 for the reason that pressure in 75 said pipe is greater than the pressure in the opposite or main brake pipe 73 side of the piston 62. While in this position the pawl 66 will readily permit the passage of the lug 68 so that the brake valve 64 may be operated 80 in the usual manner for controlling the train without interference by the pawl 66.

The pipe 58 is connected to the releasing cylinder 47 and the pressure thereby provided therein tends to move the piston 44, 85 piston stem 42 and piston 43 on the opposite end of said stem in the direction indicated in Fig. 1 of the drawings. Compression of air in the cylinder 46 by inward movement of the piston 43 will be prevented by the 90 provision of a bleeding hole 40.

As the piston stem or rod 42 moves toward the right under pressure of the air within the cylinder 47 the link 39 actuates the eccentric cam 38 to engage and bind upon the 95 knurled periphery of the large bevel gear 26 but as said gear 26 is directly connected to the axle 4 of the tender 1 it is evident that the train of gears hereinbefore described will operate as a retarding means to retard movement of the piston 44 within the releasing cylinder 47. As the piston rod or stem 42 is thus directly connected to the wheels 3 of the tender it is obvious that movement of said piston rod will be in direct proportion to the distance traveled, regardless of the speed or revolutions per minute of said wheels 3. Therefore assuming that the piston 44 is moved to its extreme inward limit 100 it is evident that the said piston cannot be moved outwardly while the tender is not in motion but can be moved outwardly while the tender is in motion but such outward movement will be in direct proportion to the distance, and not the speed, traveled by 110 said tender 1. In other words, assuming the train to be continually in motion and the piston 44 starting from its extreme inward position within the releasing cylinder 47, said piston 44 will be moved to uncover the 115 V-shaped aperture or recess 48 when a predetermined distance has been traversed by said train which distance, for convenience of illustration, I have assumed to be a quarter 120 of a mile.

When the piston 44 of the releasing cylinder 47 is moved outwardly a distance sufficient to uncover the V-shaped aperture 48 air is permitted to escape through said aperture 48 which will reduce the pressure with- 130

in the pipe 58 and also in the brake valve actuating cylinder 59, in Fig. 7 of the drawings, until the pressure on the opposite side of the piston 62 in said cylinder 59 is greater 5 and sufficient to move the piston 62 to actuate the pawl 66 which then moves inwardly and in so doing engages the lug 68 on the extension 69 of the operating lever 71 of the brake valve 64 and moves said lever 71 to "service" 10 position as indicated in dotted lines in Fig. 7 of the drawings.

Movement of said operating lever 71 to said service position will actuate the brake valve 64 and other portions of the air brake system, not shown, and bring the train to a stop. When the piston rod or stem 63 has been actuated to move the operating lever 20 15 20 to a position where the lug 68 may freely pass through the gap 65, disclosed in Fig. 9 of the drawings, at the upper end of the arcuate flange 67. In this manner a valve actuating mechanism is provided that is adapted to move the operating lever from "running" to "service" position without otherwise interfering with the operating of said lever 71 by the engineer or motorman.

Referring to Fig. 6 of the drawings we 30 will assume that the train is positioned at A and running in the direction indicated by the arrow. The track is divided into unequal insulated sections. Movement of the train will rotate the gear 26 and permit outward movement of the piston 44 in the releasing cylinder 47. But, previously to arrival of the piston 44 to the V-shaped recess 48 in said cylinder 47 the contact shoes 81 contact with the track trips 86 of the next 35 40 block, and as said block and its associated track section is clear and the circuit thereof in proper working order the track relay 96 is energized and the contacts 99 closed and therefore current from the engine battery 45 50 55 60 operation will be omitted if the said section is not "clear" and the train automatically stopped before entering said block.

It is obvious that the gear 26 must rotate 5 in the same direction regardless of the direction of movement of the train. To automatically provide for this one way rotation of the gear 26 I have provided the automatic reversing gear which operates as 10 follows:

As long as the train moves forward the beveled gear 28 attached to the end of the axle 4 will rotate the bevel gear 29 and disc 31 attached thereto in a direction which will 15 cause the pins 32 to engage the flexible end 33 of the lever 34 and retain the double ended clutch 16 on the shaft 14 in engaging relation with the bevel gear 20 to rotate the gear 26 in a clock-wise direction.

20 When the direction of movement of the train is reversed the pinion 28 rotates in the opposite direction and thereby reverses the direction of rotation of the disc 31 and pins 32 thereon. This reversal of the direction 25 of rotation of the disc 31 will cause one of the pins 32 thereon to engage the flexible end 33 of the lever 34 and move the double ended clutch member 16 into engagement with the bevel gear 19 thereby continuing the rotation 30 of the bevel gear or pinion 22 in the same direction for the reason that the bevel gear 19, now being driven by the shaft 14, is in contact with the opposite side of the gear 22 from the bevel gear 20 and the shaft 14 35 is rotating in an opposite direction.

When the train is again moved in a forward direction the pins 32 will again operate the clutch member 16 to move the gear 26 forward.

40 When the automatic stop has actuated the actuating piston 62 and the train has been brought to a stop the device may again be reset by operating the three-way valve lever 76 against the tension of the spring 75 connected thereto until the interior of the actuating cylinder 59 on the main brake pipe side of the said cylinder 59 is opened to the atmosphere and said train pipe 73 is closed. Simultaneously the arm 77 attached to said 45 lever 76 closes the switch contacts 78 in series with the engine battery 89 and solenoid 56 and thereby opens the valve 52 of the main reservoir pipe 51 and the device is reset.

55 As the main brake pipe side of the actuating cylinder 59 is opened to the atmosphere through the three-way cock or valve 74 it is evident that the pressure on the opposite side of the piston 62 in said 60 cylinder 59 will move said piston 62 and the pawl 66 pivotally connected thereto to operative position. During such movement of the piston 62 and its stem or rod 63, the spring controlled pawl 66 will be depressed 65 toward said stem or rod 63 while passing

the lug 68 should the operating lever 71 be in "holding" or "lap" position, without affecting or moving said lever 71.

It is obvious from the foregoing that I have provided an improved automatic train 70 stop adapted to automatically stop a train if the section of track being approached is not "clear." It is also obvious that the sections may be of irregular length and that the device will be controlled to stop the 75 train at the end of a clear section regardless of the length of said section, provided the next section is blocked. It is also evident that the device will be operated and controlled regardless of the direction of movement of the train, and also, that while actuating the brake valve that said brake valve always remains unobstructed and may be manipulated by the engineer or motorman without interference with the automatic 80 stop.

Having thus described my invention what I claim as new and desire to secure by Letters Patent is:

1. An automatic train stop comprising an 90 actuating means for engaging and actuating the brake valve of a standard air brake system to stop a train; controlling means for controlling the actuating means for actuating the valve; and retarding means actuated 95 by movement of said train for retarding the action of the controlling means whereby said controlling means may be operated at the ends of predetermined distances travelled by the train.

2. An automatic train stop comprising an actuating means for engaging and actuating a brake valve of a standard air brake system to stop a train; controlling means for controlling the actuating means to actuate said 105 brake valve; retarding means actuated by movement of said train for retarding the action of the controlling means through regular periods whereby said means may be operated at the ends of predetermined distances travelled 110 by the train; and means for resetting the retarding means previously to reaching to the ends of said distances when a predetermined section of a track being approached by said train is unobstructed.

3. An automatic train stop comprising an actuating means arranged to engage and move a brake valve of a standard air brake system from running to service position; controlling means for controlling the actuating means to actuate said brake valve; retarding means actuated by movement of a train for retarding the action of the controlling means through regular intervals of distance traveled by said train and to permit 120 operation of said controlling and retarding means at the end of said periods; and means for resetting said retarding means, to prevent operation of said controlling and actuating means, just previously to the end of each 125 130

regular interval when a predetermined section of track being approached by said train is unobstructed.

4. An automatic train stop comprising an actuating means arranged to engage and move a brake valve of a standard air brake system from running to service position; controlling means for controlling the actuating means to actuate said brake valve; retarding means actuated by movement of a train for retarding the action of the controlling means through regular intervals of distance traveled by said train and to permit operation of said controlling and retarding means at the end of said periods; and means for resetting said retarding means, to prevent operation of said controlling and actuating means, just previously to the end of each regular interval when a predetermined section of track being approached by said train is unobstructed; and means for operating the retarding means in the same direction when the direction of movement of the train is reversed.
5. An automatic train stop comprising an actuating means arranged to engage and move a brake valve of a standard air brake system from running to service position; controlling means for controlling the actuating means to actuate said brake valve; retarding means actuated by movement of a train for retarding the action of the controlling means through regular intervals of distance traveled by said train and to permit operation of said controlling and retarding means at the end of said periods; and means for resetting said retarding means, to prevent operation of said controlling and actuating means, just previously to the end of each regular interval when a predetermined section of track being approached by said train is unobstructed; and auxiliary means for resetting the retarding and actuating means independently of the previously mentioned resetting means.

6. An automatic train stop comprising an actuating means arranged to engage and move a brake valve of a standard air brake system from running to service position to stop a train; controlling means for controlling the actuating means to actuate the brake valve and stop the train; means actuated by the movement of a train in either direction for retarding the operation of said controlling means and for permitting such operation at the end of regular intervals of distance traversed by said train; and means for resetting the controlling means just previously to said controlling operation to prevent the same when an interval of track being approached by said train is clear.

7. An automatic train stop comprising an actuating means arranged to engage and move a brake valve of a standard air brake system from running to service position to

stop a train; controlling means for controlling the actuating means to actuate the brake valve and stop the train; means actuated by the movement of a train in either direction for retarding the operation of said controlling means and for permitting such operation at the end of regular intervals of distance traversed by said train; and means for resetting the controlling means just previously to said controlling operation to prevent the same when an interval of track being approached by said train is clear; and for preventing operation of said resetting means when said interval is obstructed.

8. The combination with a track comprising insulated sections, of actuating means for engaging and actuating a brake valve of a standard brake system to move the same from running to service position; controlling means for controlling the actuating means to permit operation of the same at regular intervals of distance traversed by a train on said track sections; retarding means actuated by the movement of said train to retard the action of the controlling means until near the end of an interval; resetting means arranged to reset the controlling means; and means actuated by an unobstructed track section being approached by said train for operating the resetting means just previously to the entrance of said train on said section.

9. The combination with a series of insulated track sections of various lengths, of actuating means arranged to engage and actuate a brake valve of a standard air brake system of a train to move said valve from running to service position to stop said train; controlling means arranged to control said actuating means to actuate said valve; retarding means actuated by movement of said train and arranged to retard the action of the controlling means through regular intervals of distance and to permit operation of said controlling means at the end of said interval; and resetting means arranged to be actuated by an unobstructed section being approached by the train for resetting the controlling and retarding mechanism at regular and predetermined distances in advance of the farther end of a track section being approached by said train.

10. In an automatic train stop, the combination of a series of insulated track sections; trips positioned a predetermined distance from the ends of said sections; brake valve actuating mechanism arranged to engage and actuate the brake valve of a train from running to service position; controlling means for controlling the actuating mechanism to actuate the brake valve; retarding means actuated by movement of a train in either direction to retard the action of said controlling means through regular intervals of distance traversed by said train; and re-

setting means actuated by said air brake system and said trips to reset the controlling and retarding means in advance of an unobstructed track section being approached and 5 a predetermined distance in advance of the farther end of said section.

11. In an automatic train stop, the combination of a series of insulated track sections; trips positioned a predetermined distance 10 from the ends of said sections; brake valve actuating mechanism arranged to engage and actuate the brake valve of a train from running to service position; controlling means for controlling the actuating mechanism 15 to actuate the brake valve; retarding means actuated by movement of a train in either direction to retard the action of said controlling means through regular intervals of distance traversed by said train; and re- 20 setting means actuated by said air brake system and said trips to reset the controlling and retarding means in advance of an unobstructed track section being approached and a predetermined distance in advance of the

farther end of said section; and means for 25 resetting the controlling and retarding means independently of the trips.

12. An automatic train stop comprising an actuating means arranged to engage and actuate a brake valve of a train having a 30 standard air brake system to stop said train; controlling means for controlling the actuating means at regular intervals of distance traveled by said train; retarding means actuated in operative direction by forward 35 movement of said train to retard the action of the controlling means through said regular intervals of distance; means for resetting the controlling and retarding means previously to the end of an interval when a predetermined section of track being approached is unobstructed; and means for automatically retaining movement of the retarding means in the operative direction when the direction of said train is reversed. 40

In witness whereof I hereunto set my signature.

THOMAS M. RIGGLE.
